UNITED STATES PATENT OFFICE.

CHARLES H. BOMBARDIE, OF SOUTH BEND, INDIANA, ASSIGNOR TO WIREBOUNDS PATENTS COMPANY, OF KITTERY, MAINE, A CORPORATION OF MAINE.

BOX-MAKING MACHINE.

1,371,598.

Specification of Letters Patent. Patented Mar. 15, 1921.

Application filed December 29, 1916. Serial No. 139,508.

To all whom it may concern:

Be it known that I, CHARLES H. BOMBARDIE, a citizen of the United States, and a resident of South Bend, in the county of St. Joseph and State of Indiana, have invented an Improvement in Box-Making Machines, of which the following description, in connection with the accompanying drawings, is a specification, like characters on the drawings representing like parts.

This invention relates to machines for use in making wirebound boxes and the like and among other objects is intended to provide improved means for controllably positioning the driven fasteners for securing the box materials together and the binding wires thereto, no matter what the distances between the several fasteners may be or how much they may vary. As a particular use of the invention I point out the production of wirebound box blanks wherein a number of side sections have connecting binding wires stapled thereto. In making such blanks it is desirable to locate the staples definitely with relation to the edges of the sections and to space them in some particular way along the same.

In the accompanying drawings I have illustrated as an embodiment of my invention a machine of a type generally well known and one adapted to construct a wirebound box blank. My invention will best be understood by reference to the following description taken in connection with these drawings, wherein:

Figure 1 is a side elevation of one end of a machine embodying my invention;

Fig. 2 is a section on line 2—2 of Fig. 1;

Fig. 3 is a section on line 3—3 of Fig. 2; and

Fig. 4 is a detail of part of the driving train.

Referring to Figs. 1 and 2, I have there illustrated a machine embodying a stapling mechanism and a circulating carrier for the box materials which is adapted to move the latter beneath the stapling mechanism for operation of the latter thereon. This type of machine is in general well known and the illustration herewith of one end thereof will enable those skilled in the art to understand the construction. The carrier for the box materials may take the form of suitable chains 3 adapted to receive box cleats and trained over sheaves 5, of which one set is

shown in the drawings. A stapler head best illustrated in Fig. 2, is positioned over the path of the conveyer mechanism and comprises staplers 5, shown diagrammatically in Fig. 2, to which continuous binding wires may be supplied in a well-known manner. Said staplers are supported on the cross bar 7 of the machine and on the reciprocating crosshead 9 adapted to be actuated at either side of the machine by the pitman 11 and eccentric 13 (see Fig. 1) to drive staples over the binding wires into the material presented beneath the head of the conveyer chains 3. Suitable means (not illustrated) may be provided for applying binding wires to the blank. All this construction is of familiar form and is in itself no part of my present invention.

In accordance with my invention I provide means whereby the points of any arbitrarily chosen series along the conveyer chain, and in consequence along the blank materials sustained thereby, may be presented in succession to the stapler head for operation of the staplers thereon upon successive reciprocations of the crosshead 9. For this purpose the carrier or conveyer may be provided with a yieldable advancing means for feeding the materials beneath the stapler head, and means may be provided for checking the movement of the conveyer and consequently of the materials at proper times in correlation with the reciprocations of the stapler head so as to cause staples to be driven at desired points.

In the present embodiment of the invention the conveyer chains are driven from the main shaft 15 by a suitable train providing for lost motion under excessive strain which train may include a suitable frictional couple. Means are provided for halting the conveyer for holding it stationary against the driving action of this train while the staple is being driven.

Referring particularly to Figs. 1 and 4, I have there shown one suitable mechanism by which the conveyer chains 3 may be advanced through the sheaves 5 from the main shaft 15 of the machine. The mechanism illustrated comprises a worm shaft 17 driven by the miter gears 19 from the main shaft 15, and transmitting motion through worm wheel 21 to friction disk 23 both of which members are on the sleeve 25 supported by and free to turn on the axle 27 of the

sheave 5. Splined to the axle 27 is a friction disk 29 adapted to coöperate with the disk 23. If desired the disk 29 may be pressed against the disk 23 by spring 31 the 5 tension of which, in the embodiment shown, may be adjusted by means of a nut 33 threaded on axle 27 to vary the pressure on the disk 29. It is apparent that when the main driving shaft 15 of the machine is rotated 10 power will ordinarily be transmitted through the frictional couple 23-29 to rotate the sheaves 5 and so move the conveyer chain but that, if there is excessive resistance to movement of chains 3, the disk 29 will slip on disk 23 and the movement of the latter will be an idle movement not affecting the chains.

The worm on shaft 17 cannot readily be turned by the wheel and so the resistance to 20 movement of the conveyer is not communicated to the shaft 15 in such a manner that slippage of the main driving belt might occur. However, I do not wish to be limited to the particular form of train shown.

25 The motion transmitted to the conveyer chains 3 is of sufficient rapidity to move the latter through the maximum distance which it is desired to have between staples in the interval between successive reciprocations of 30 the stapler head. Means are provided to halt the conveyer chain when any desired length thereof has moved beneath the stapler head after the last operation of the latter and to hold the same until the next staple 35 is driven. I will now describe, with reference particularly to Figs. 2 and 3, one suitable mechanism for accomplishing this purpose. I have in those figures shown catches 35 adapted to coöperate with adjustable 40 stop members 37 on the conveyer chains. Stop members 37 may take the form of pins and the conveyer chains are provided with holes 39 at suitable intervals into which the pins may be fitted. When a stop pin 37 is in 45 contact with the catch 35 as shown in Fig. 3 the chain which carries it is held against movement and the stapler head descending will drive the staple in the box material which is supported by the conveyer chain 50 immediately above or adjacent the point where the stop pin 37 is placed.

The catches 35 may take the form of links 41 pivoted at one end to blocks 43 sustained on the frame of the machine and having 55 abutments 45 adapted to coöperate with the stop pins. The link 41 is normally depressed as by a suitable spring 47 so that the abutment 45 is presented in the path of the stop pins 37 on the conveyer chain 3. Means are 60 provided correlated in action with the stapler head for tripping the catches in order to release the conveyer chains to permit a further feeding movement of the box material. In the present embodiment of the invention this means takes the form of latches 65

49 carried by the crosshead 9 to which they are pivoted, as clearly shown in Fig. 3. The latch 49 is provided with a beveled end 51 and a hook portion 53 adapted to coöperate with a pin 55 on link 41 of the catch. When 70 the crosshead 9 descends in the stapling operation the beveled portion 51 of the latch will contact with pin 55 and the former will be swung to the left by the cam action of the bevel to permit the pin to enter the hook 75 53 which will swing into engagement with the same when the latch again hangs down straight. As the crosshead 9 rises the link will swing upwardly on its pivot against the force of spring 47 releasing stop pin 37 80 from the abutment 45. Cross bar 7 is provided with a guide 57 in which the latch 49 runs and this guide is provided with a cam surface 59 adapted to coöperate with a pin 61 on the latch. After the latch in ascending has swung the catch clear of the stop pin the cam surface 59 of the guide will act on pin 61 to swing the latch once again to the left and thereby to disengage the hook portion of the same from the pin 55. The link 90 41 will then drop aided by the action of spring 47 and the abutment surface 45 will be in position to engage the next stop pin on the conveyer chain to halt the latter once again at the proper point for the driving 95 of the next staple.

It will be apparent from the description given of one embodiment of the invention that I provide means whereby fastening devices such as staples can be accurately fastened in any desired special relation and at 100 selected points on the work. The stop pins 37 may be adjusted along the length of the conveyer chains in the position in which it is desired to have the staples placed, using the 105 blank as a guide if desired, and the chains will be halted when those points arrive beneath the stapler head so that staples will be driven there. The spacing is entirely arbitrary and not only may the relation of 110 staples on a single blank be varied but the distances between the blanks can be readily cared for without causing a useless staple to be formed and driven between blanks. Furthermore, the positioning of the staples is 115 controlled directly from the materials themselves, that is, by pins on the work conveyer placed relatively to the materials which are being held and moved forward by the conveyer, and not by a process which locates the 120 staples of a series by determining their distances from the first of that series. In the latter method there is a possibility for accumulated error and furthermore, when the machine moves from one blank to another it 125 is necessary in practice to provide some means for bringing the mechanism back to a starting or zero point. This is provided for in the present machine automatically in the regular operation thereof. 130

In machines of the general type shown in the drawing such as hitherto have been known there have been various factors contributing to an inaccurate positioning of the staples. In order to reduce the number of joints in the conveyer chain and thereby minimize the possibility of having to place spacing blocks for the cleats at such joints, the links of the chains have been made quite long and the sheaves 5 therefore of markedly polygonal form. The use of these polygonal sheaves has given an irregular drive to the chains since the effective crank arm thereof varies according as to whether 10 an apex or a side of the polygon is uppermost. This source of error is entirely eliminated in the present mechanism since the portion of the chain beneath the stapler head at the time the latter descends is not directly dependent upon the distance the sheave 5 has been driven. The present construction also eliminates the difficulties hitherto experienced in the unequal movement of the two chains which has caused the 15 sides of the box blank to get out of alignment. If the stop pins are positioned opposite each other both chains will be stopped after having moved the same distance independently of slight differences of movement due to inaccuracies of the driving mechanism therefor and the staples will be fastened in exact alignment across the box blank.

It will be apparent from the above description of a single illustrative embodiment of my invention that I have provided a simple and effective machine whereby fasteners may be driven into materials in any desired relative position. In explaining the 20 machine shown in the drawings, I have described the same in considerable detail and named specifically the different parts of the mechanism shown. It will be understood, however, that I have done this in order that the structure and operation might be more readily understood and not because these matters of detail are essential to my invention, but that what I do claim and desire to secure by Letters Patent is:

50 1. A machine of the class described comprising a circulating conveyer for box materials, a power shaft, a train between said power shaft and conveyer providing for lost motion under excessive strain, abutments on said conveyer, stop means in the path of said abutments, a stapler head, and means correlated in action with said head for withdrawing said stop means from the path of the abutments.

60 2. A machine of the class described comprising a circulating conveyer for box materials, a power shaft, a train between said power shaft and conveyer providing for lost motion under excessive strain, abutments carried by said conveyer and arranged to be

positioned at will at desired intervals therealong, stop means in the path of said abutments, a stapler head, and means correlated in action with said head for withdrawing said stop means from the path of the abutments. 70

3. A machine of the class described comprising a circulating conveyer for box materials, means for driving the same, said means being constructed and arranged to provide for relative lost motion, adjustable abutments distributed along said conveyer, a catch normally resting in the path of said abutments, a stapler head, and means carried thereby to throw said catch. 80

4. A machine of the class described comprising a circulating conveyer for box materials, means for driving the same, said means being constructed and arranged to provide for relative lost motion, abutments distributed along said conveyer, a catch normally resting in the path of said abutments, a stapler head, a latch carried thereby and adapted to snap into engagement with said catch on descent of the stapler head, and means to disengage the latch from the catch on reverse movement of the head. 85

5. A machine of the class described comprising a pair of parallel cleat-carrying chains, means for driving the same, said means being constructed and arranged to provide for lost motion, adjustable abutments on said chains, aligned catches co-operating with said abutments, a stapler head, and means correlated in action with said head for releasing said catches. 95

6. A machine of the class described comprising a circulating conveyer for box materials, means for driving the same, said means being constructed and arranged to provide for relative lost motion, adjustable abutments distributed along said conveyer, a catch spring-pressed into the path of said abutments, a stapler head, and means acting periodically in correlation with said head 105 for moving the catch against the action of the spring and away from the abutments. 110

7. A machine of the class described, adapted for uninterrupted operation upon materials for a plurality of boxes, including as elements a stapling and binding-wire-applying mechanism and a work holder, means for relatively moving the same to a series of positions for application of staples to the work on said holder comprising a yieldable advancing means and a set of members arranged for successive action to halt one of said elements against the action of said advancing means. 115

8. A machine of the class described including as elements a stapling mechanism and a work holder, yieldable means for relatively moving the same and a set of members relatively adjustable to positions corresponding to selected relative positions 120 125 130

- of said elements, said members being presented in succession and acting to halt relative movement of said elements against the action of said means.
5. 9. A machine of the class described adapted for uninterrupted operation upon materials for a plurality of boxes including as elements a stapling mechanism and a work holder, continuously acting means 10 for relatively moving the same, and members arranged for successive presentation in correlation with such movement to intermittently lock said work holder against movement.
15. 10. A machine of the class described comprising, in combination a carrier for box materials, a stapling mechanism and means to cause relative movement of said mechanism and of work on said carrier, members 20 positionable in direct spacial relation to the points in an arbitrarily chosen series along the work, and means coöperating with said members to halt the relative movement referred to to effect at such times the driving 25 of staples at such points.
11. A machine for use in making wire-bound boxes comprising, in combination, binding-wire applying mechanism; work-supporting means; means for relatively 30 moving said mechanism and work; and automatic means to determine a desired relationship between said mechanism and work at the time of a wire-securing operation including a member adjustable longitudinally of the work in fixed relation to a desired wire-securing point on the work and a stop arranged to engage said member and thereby arrest the relative progression when 35 said point on the work so related to said 40 member is in position to receive a wire fastening.
12. A machine for use in making wire-bound boxes comprising, in combination, binding-wire applying mechanism; work-supporting means; means for relatively 45 moving said mechanism and work; and automatic means to determine a desired relationship between said mechanism and work at the time of a wire-securing operation, comprising a member fixed in relation 50 to the work at a desired wire-fastening point thereof and a stop normally in the path of said member to engage the same at the wire-securing point to arrest the relative movement.
55. 13. A machine for use in making wire-bound boxes comprising, in combination, binding-wire applying mechanism; work-supporting means; means for relatively 60 moving said mechanism and work; and automatic means to determine desired relationships between said mechanism and work at the time of wire-securing operations, comprising a set of members in fixed 65 relation to the work correlated with desired
- relative positions of work and mechanism and a stop normally in the path of said members to coact therewith to arrest the progression.
14. A machine for use in making wire-bound boxes comprising, in combination, means including fastener-setting mechanism to secure binding wire to box parts; work supporting means; and means for causing a variable relative progression between the work and fastener-setting mechanism in controlled steps for definitely locating fasteners on the work, which comprises a series of members distributed along the work at and in fixed relation to desired fastener-receiving points, and means coöperating with said members in succession automatically regulating the progression to cause presentation successively to the fastener-setting mechanism of said points of the work at which said members are arranged.
15. A machine for use in making wire-bound boxes comprising, in combination, means including fastener-setting mechanism to secure binding wire to box parts; work-supporting means; and means for causing a variable relative progression between the work and fastener-setting mechanism in controlled steps for definitely locating fasteners on the work, which comprises a series 95 of members distributed along the work at and in fixed relation to desired fastener-receiving points thereon, and stop means to coöperate with said members in succession for successively arresting the progression with said points of the work presented to the fastener-setting mechanism.
16. A machine for use in making wire-bound boxes comprising, in combination, means including fastener-setting mechanism 105 to secure binding wire to box parts; work-supporting means; and means to cause a variable relative progression between the work and fastener-setting mechanism in regulated steps for definitely locating fasteners on the work, comprising a series of members distributed along the work in similar fixed relations to a corresponding series of desired fastener-receiving points thereon, and stop means to coöperate with said members in succession for successively arresting the progression with said points of the work presented to the fastener-setting mechanism.
17. A machine for use in making wire-bound boxes comprising, in combination, means including fastener-setting mechanism 110 to secure binding wire to box parts; work-supporting means; and means for causing a variable relative progression between the work and fastener-setting mechanism in controlled steps for definitely locating fasteners on the work, comprising a series of independently positionable members distributed along the work in similar fixed re- 125
- 130

lations to a corresponding series of desired fastener-receiving points thereon, and stop means to coöperate with said members in succession for successively arresting the 5 progression with said points of the work presented to the fastener - setting mechanism.

18. A machine for use in making wire-bound boxes comprising, in combination, 10 means including fastener-setting mechanism to secure binding wire to box parts; work-supporting means; and means for causing a variable relative progression between the work and fastener - setting mechanism in 15 controlled steps for definitely locating wire fasteners on the work, comprising a series of independently positionable members distributed along the work at desired fastener-receiving points and in fixed relation thereto, 20 and means coöperating with said members in succession automatically regulating the progression to cause presentation successively to the fastener-setting mechanism of said points of the work at which said 25 members are arranged.

19. A machine for use in making wire-bound boxes comprising, in combination, mechanism to secure binding-wire to box parts; work-supporting means; and means 30 for relatively moving said mechanism and work to a series of positions for successively securing the wire at a series of desired intervals, including means yieldingly causing progression at a speed sufficient for moving a maximum interval between successive 35 actions of the wire-securing mechanism, a set of traveling members arranged according to desired intervals, and a stop normally in the path of said members to coat 40 therewith in succession to arrest the progression.

20. In a machine for making wirebound boxes by progressively wiring box-forming material, the combination with mechanism 45 to secure the binding wires, and means to support the work for proper presentation thereto, of means for causing an irregular relative progression between the work and wire-securing mechanism in controlled steps 50 for applying wire fasteners according to a desired disposition thereof on the work, comprising yieldable advancing means operating at a speed sufficient to impart a movement between consecutive wire-securing 55 operations of a required maximum for variable fastener - spacing and joint-skipping, means to arrest the progression, and means automatically successively coöperating 60 with said arresting means in accordance with the desired disposition of fasteners.

21. In a machine for making wirebound boxes by progressively wiring box-forming material, the combination with mechanism to secure the binding wires, and means for 65 supporting the work for proper presenta-

tion thereto, means for causing relative progression between the work and wire-securing mechanism in regulated steps for definitely locating fasteners at desired points on the work, comprising yieldable 70 advancing means operating at a speed sufficient to impart a movement between consecutive fastener-setting operations of a required maximum for variable fastener-spacing and joint-skipping, and automatic 75 stop means controlled in accordance with successive presentations to the fastener-setting mechanism of said desired points on the work for arresting the relative progression 80 against the action of said advancing means.

22. A machine for use in making wire-bound boxes comprising, in combination, means to secure binding wire to box parts; work-supporting means; and means for relatively moving the work and the wire-securing means to a series of positions for securing the wire at a succession of desired points on the box parts, comprising yieldable advancing means operating at a speed 90 sufficient to impart a maximum spacing and joint skipping movement between consecutive wire-securing operations, and a set of members correlated with desired relative positions of the work and the wire-securing 95 means arranged for successive relative presentation to arrest the relative progression against the action of said advancing means.

23. A machine for use in making wire-bound boxes comprising, in combination, means to secure binding wire to box parts; work-supporting means; and means to cause relative progression between work and wire-securing means in regulated steps for 100 applying wire fasteners according to a desired arrangement, comprising motion-imparting mechanism constructed and arranged to permit lost motion and to impart a movement between consecutive wire-securing 105 operations of sufficient magnitude for the maximum progression required for variable spacing and joint-skipping, a set of members fixed in relation to the work according to such desired arrangement of 110 wire fasteners, and stop means in the path of said members to coat successively therewith to arrest the relative progression.

24. A machine for use in making wire-bound boxes comprising, in combination, 115 mechanism to secure binding wire to box-forming material; work-supporting means; and means for causing relative progression between said wire-securing mechanism and the work in controlled steps for definitely 120 positioning wire fastenings on the work, comprising a motion-imparting mechanism constructed and arranged to permit lost motion and to impart a relative movement between consecutive wire-securing operations 125 130

of sufficient magnitude for the maximum progression required for variable spacing and joint-skipping, and a set of members correlated with desired relative position of 5 the work and the wire-securing mechanism arranged for successive relative presentation to arrest the relative progression.

25. A machine for use in making wire-bound boxes comprising, in combination, 10 means to secure binding wire to box parts; work-supporting means; and means for relatively moving work and wire-securing means in regulated steps for securing the binding wire at desired points on the work, 15 comprising motion-imparting means constructed and arranged to permit lost motion and to impart a movement between consecutive fastener-setting operations of sufficient magnitude for the maximum progression required for variable spacing and joint skipping, a set of members arranged in fixed relations to the work according to desired positions of wire-fastenings, and stop means 20 normally positioned for coaction with said members successively to arrest the relative 25 progression.

26. A machine for use in making wire-bound boxes by progressively wiring box-forming material, which comprises, in combination, 30 means to secure the binding wires; coöperating work-supporting means; and means for causing an irregular relative progression between the work and the wire-securing means in steps of controlled length 35 for definitely locating the wire fastenings on the work, comprising motion-imparting mechanism constructed and arranged to permit lost motion and to impart a movement between consecutive wire-securing, operations 40 of sufficient magnitude for the maximum progression required for variable spacing and joint skipping, a set of members correlated with desired relative positions of the work and the wire-securing means and 45 arranged for successive presentation in correlation with a succession of such movements, and means successively coöperating therewith for regulating the cessations of such movements.

50. 27. In a machine for making wirebound boxes by uninterrupted progressive action of wire-securing mechanism upon a succession of box assemblies, an automatic means to produce a skip feed to prevent the application of wire fasteners at box joints, comprising means for yieldingly forwarding the work at a sufficient speed for the skip feed and means effective after a wire-securing 55 operation for rendering said forwarding 60 means operative.

28. A machine for use in making wire-bound boxes comprising, in combination, binding wire applying mechanism; work-supporting means; yieldably operating 65 means for relatively advancing the work

and the wire-applying mechanism at a speed sufficient to impart a maximum spacing and joint skipping movement between consecutive wire-fastening operations; a set of members arranged in fixed relation to the 70 work according to a desired disposition of fasteners; and stop means normally in the path of said members to arrest the relative movement against the action of said advancing means. 75

29. A machine for use in making wire-bound boxes comprising, in combination, binding wire applying mechanism; work-supporting means; yieldably operating means for relatively moving work and wire-applying mechanism at a speed sufficient 80 to impart a maximum spacing and joint skipping movement between consecutive wire-fastening operations; a set of members arranged in fixed relation to the work 85 according to a desired disposition of fasteners; and stop means normally in the path of said members to arrest the relative movement against the action of said advancing means, and means correlated in action with 90 said wire-applying mechanism for automatically releasing said stop means and members from engagement.

30. A machine for use in making wire-bound boxes comprising, in combination, 95 binding-wire attaching mechanism; work-supporting means; yieldably operating means for relatively moving work and wire-attaching mechanism; a set of members positioned along the work in fixed relation to 100 selected attaching points; and means successively coactive therewith to arrest the relative movement with said points presented to the wire-attaching mechanism.

31. A machine for use in making wire-bound boxes comprising, in combination, 105 means to secure binding wire to box parts; continuously operating means for feeding thereto a succession of box assemblies, including means for yieldingly advancing the 110 work at a speed sufficient for a maximum spacing and joint-skipping movement between consecutive wire-securing operations; and automatic means controlled in accordance with the presentation to the wire-securing means of a succession of desired wire-securing points on the box assemblies for 115 arresting movement of said box assemblies.

32. A machine for use in making wire-bound boxes comprising, in combination, 120 means to secure binding wire to box assemblies; means for feeding thereto a succession of box assemblies, including continuously operating means for yieldingly advancing the work at a speed sufficient for a maximum spacing and joint-skipping movement between consecutive wire-securing operations; and coöperating means for controllably positioning wire fastenings comprising a 125 set of members correlated with selected rela- 130

- 5   32. A machine for use in making wire-bound boxes comprising, in combination, work-supporting means for holding cleats and side material in relationship to be secured together and for application of binding wire thereto; mechanism to fasten such box parts together and to secure the binding wire thereto; and means for relatively moving said mechanism and work to a series of selected positions for operation at desired points on the work, including stop means and a set of members arranged parallel to the length of the cleats in a relationship corresponding to said desired points, said members coöperating successively with said stop means to arrest the relative movement. 10
- 10   33. A machine for use in making wire-bound boxes comprising, in combination, means to secure binding wire to box parts; continuously operating means for feeding thereto a succession of box assemblies, including means for yieldingly advancing the work at a speed sufficient to impart a maximum spacing and joint-skipping movement between consecutive actions of the wire-secur ing means; stop means for arresting the movement of said box assemblies; and means automatically coöperating with said stop means a plurality of times for a given box assembly. 15
- 15   34. A machine for use in making wire-bound boxes comprising, in combination, work-supporting means for holding cleats and side material in relationship to be secured together and for application of binding wire thereto; mechanism to fasten such box parts together and to secure the binding wire thereto; and means for relatively moving said mechanism and work to a series of selected positions for operation at desired points on the work, including stop means and a set of members arranged parallel to the length of the cleats in a relationship corresponding to said desired points, said members coöperating successively with said stop means to arrest the relative movement. 20
- 20   35. A machine for use in making wire-bound boxes comprising, in combination, work-supporting means for holding cleats and side material in relationship to be secured together and for application of binding wire thereto; mechanism to fasten together said box parts and secure binding wire thereto; and means for relatively moving said mechanism and work holder to a series of selected positions for operation at desired points on the work, including a set of members arranged parallel to the length of the cleats at desired fastening points and means coöperating with said members in succession for determining movements to present said points to said mechanism. 25
- 25   36. In a machine for use in making wire-bound boxes, by progressive action of wire-secur ing mechanism upon assembled box parts, the combination of said mechanism, work-supporting means, and feed mechanism to cause relative progression between said mechanism and work, in a continuously operating organization for wiring a succession of assembled parts for successive boxes; pattern means comprising a set of members arranged respectively at desired wire-fastening points; and means successively coöperating therewith for relatively positioning said mechanism and work to receive the wire fastenings at said points. 30
- 30   37. In a machine for use in making wire-bound boxes, by progressive action of wire-secur ing mechanism upon assembled box parts; the combination of said mechanism, work-supporting means, and feed mechanism to cause relative progression between said mechanism and work, in a continuously operating organization for wiring a succession of assembled parts for successive boxes; and automatic means for determining desired relationships between said mechanism and work at the time of wire-secur ing operations, including a set of members arranged for successive action to arrest the relative progression. 35
- 35   38. A machine for use in making wire-bound boxes comprising, in combination, means to secure binding wire to box parts; work-supporting means; means to cause relative progression between said mechanism and work; said elements constructed and arranged to provide a continuously operating organization for wiring successive box assemblies; and coöperating fastener-positioning means for controllably locating individual wire fastenings on successive box assemblies, comprising a set of members correlated with chosen wire fastening points and arranged for successive action to arrest the relative progression. 40
- 40   39. A machine for use in making wire-bound boxes comprising, in combination, means to secure binding wire to box parts; work-supporting means; means to cause relative step movements between said mechanism and work; said elements constructed and arranged to provide a continuously operating organization for wiring successive box assemblies; and coöperating fastener-positioning means for controllably locating individual fasteners on successive box assemblies, comprising means controlled in accordance with the passage of desired wire-fastening points on said assemblies for regulating the cessations of said relative step movements. 45
- 45   40. A box-blank machine comprising, in combination, coöperating blank-feeding and binding-wire applying mechanisms in a continuously-operating organization for wiring successive blanks; and automatic means for determining desired relationships between successive blanks and the binding-wire applying mechanism for securing the binding wires at desired points on the blanks, comprising members set respectively at said points on successive blanks and means coöperating with said members in succession for determining feed movements to bring such points to position for operation of the wire-applying mechanism thereof. 50
- 50   41. A box-blank machine comprising, in combination, coöperating blank-feeding and binding-wire applying mechanisms in a continuously-operating organization for 55

- wiring successive blanks; said blank-feeding means constructed and arranged for yieldably advancing the blanks at sufficient speed to impart a feed movement between 5 successive operations of the wire-applying mechanism as great in extent as the maximum distance required between successive wire fastening points; and means automatically controlled in accordance with the passage of desired wire-fastening points on successive blanks for arresting the movement of the work when such points are successively in position for operation of the wire-applying mechanism thereat. 10
42. A box-blank machine comprising in combination, coöperating blank-feeding and binding-wire applying mechanisms in a continuously-operating organization for wiring successive blanks; said blank-feeding means comprising continuously-driven means for yieldingly advancing the work; and automatic means, including a set of irregularly spaced members correlated with desired relative positions of the work and 20 binding-wire applying mechanism for successively stopping the movement of the work in such selected relative positions. 25
43. A machine for use in making wire-bound boxes, constructed and arranged for uninterrupted operation upon materials for a plurality of boxes comprising, in combination, a work support, fastener-setting and binding-wire-applying mechanism, means to cause relative progression between the work 30 and said mechanism, and means to control said relative progression by automatically arresting the same at selected times. 35
44. A machine for use in making wire-bound boxes constructed and arranged for uninterrupted operation upon materials for a plurality of boxes comprising, in combination, a work support; fastener-setting mechanism; means to cause relative progression between the work and said mechanism; and coöperating stop means and pattern 40 means to control said relative progression by automatically arresting the same according to said pattern. 45
45. A machine for use in making wire-bound boxes constructed and arranged for uninterrupted operation upon materials for 50
- a plurality of boxes comprising, in combination, a work support; fastener-setting mechanism; means to cause relative progression between said mechanism and the work; and progression arresting means to control said relative progression to locate fasteners where desired on the work, including a pattern of members corresponding to the desired location of fasteners on a work assembly adapted to operate uninterruptedly to control the location of fasteners on a succession of work assemblies according to said pattern. 55
46. A machine for use in making wire-bound boxes comprising, in combination, a work support; fastener-setting and binding-wire-applying mechanism; means to cause relative progression between said mechanism and the work; and means for automatically stopping said relative progression during fastener-setting operations; said means being constructed and arranged for continuous automatic operation upon a succession of box assemblies. 60
47. A machine for use in making wire-bound boxes comprising, in combination, a work support; fastener-setting and binding-wire-applying mechanism; means to cause relative progression between said mechanism and the work; and means for automatically stopping said relative progression at selected times to locate fasteners on the work; said means being constructed and arranged for continuous automatic operation upon a succession of box assemblies. 65
48. A machine for use in making wire-bound boxes comprising, in combination, fastener-setting mechanism for applying binding wire to box parts; work-supporting means; means for relatively moving the work and said mechanism; a set of members positioned along the work in fixed relation to selected fastener-receiving points thereon; and means successively co-active therewith to arrest the relative movement as each of said points is presented to the fastener-setting mechanism. 70
- In testimony whereof I have signed my name to this specification. 75

CHARLES H. BOMBARDIE.
